UNITED STATES PATENT OFFICE.

CHARLES N. GALLAND, OF MINNEAPOLIS, MINNESOTA, ASSIGNOR TO MULTICOLOR PRINTING AND MACHINERY COMPANY, OF MINNEAPOLIS, MINNESOTA, A CORPORATION OF SOUTH DAKOTA.

CYLINDRICAL TYPE-BORDER.

1,331,637.

Specification of Letters Patent. Patented Feb. 24, 1920.

Application filed July 15, 1918. Serial No. 244,925.

To all whom it may concern:

Be it known that I, CHARLES N. GALLAND, a citizen of the United States, residing at Minneapolis, in the county of Hennepin and 5 State of Minnesota, have invented certain new and useful Improvements in Cylindrical Type-Borders; and I do hereby declare the following to be a full, clear, and exact 10 description of the invention, such as will enable others skilled in the art to which it appertains to make and use the same.

This invention has for its object to provide as an improvement in printing devices a so-called knock-down metallic printing 15 border, and to such ends generally stated, the invention consists of the novel construction and combinations of parts hereinafter described and defined in the claims.

In the accompanying drawings which 20 illustrate the invention, like characters indicate like parts throughout the several views.

Referring to the drawings:

Figure 1 is a plan view with some parts broken away showing the border applied to 25 the cylinder of a press;

Fig. 2 is a fragmentary view showing one corner portion of the printing border;

Fig. 3 is an enlarged section taken approximately on the line 3—3 of Fig. 1;

30 Fig. 4 is a transverse section taken approximately on the line 4—4 of Fig. 1; and

Fig. 5 is a view corresponding in the line of its section to Fig. 4, but showing only the printing border.

35 The cylinder 6 is secured to a shaft 7 shown as equipped with a gear and certain other devices not necessary for the purposes of this case to consider. The cylinder is provided with a plurality of longitudinal circumferentially spaced rows of threaded perforations 8.

A pair of circumferentially spaced longitudinal clamping bars 9 are adjustably secured to the cylinder by screws 10 screwed 45 into certain of the perforations 8. For cooperation with the bars 9 a pair of curved end clamping bars 11 are secured to the cylinder by screws 12 that work through slots 13 in said bars 11. The slots 13 permit 50 slight adjustments of the bars 11 after they are loosely attached to the cylinder.

The cylindrical printing border is made up of a pair of parallel circumferentially

spaced longitudinally extended printing bars 14 and curved end printing bars 15. At 55 their outer faces, the bars 14 have printing ribs 14^a preferably of materially less width than the said bars 14, but extended from end to end thereof, and likewise, the curved printing bars 14 have projecting printing 60 ribs 15^a. The ribs 14^a and 15^a when inked will print a rectangular border under rotation of the cylinder. The ends of the bars 14 are reduced in width to the width of the printing ribs 14^a thereof, and these reduced 65 ends are rigidly, but detachably, secured to the ends of the curved bars 15 by screws 16. The rectangular border thus made up of the bars 14 and 15 is a knock-down structure in which the straight bars 14 may be used with 70 curved bars 15 of different length, or the said curved bars 15 may be used with straight bars 14 of different lengths, thereby providing an interchangeable element printing border by the provision of a plurality 75 of the said bars varying in length.

For holding the printing border on the cylinder, the curved clamping bars 11 and the curved printing bars 15 are formed with interlocking V-shape groove and rib joints 80 17, best shown in Fig. 3. The clamping bars 9 are simply set up snugly against the straight printing bars 14. The printing border described is adapted to hold in position within it a multiplicity of interlocking 85 type 18, the end members of which are anchored to the curved bars 15 by tongue and groove joints 19. Of course, also printers' furniture may be secured in the frame in like manner. 90

What I claim is:

1. A cylinder printing border made up of straight side bars and curved end bars, one of the said end bars having a projecting lock flange and the other a lock groove for interlocking engagement with interlocking type 95 or the like.

2. The combination with a cylinder, circumferentially spaced straight clamping bars, coöperating curved end clamping bars 100 and means for adjustably securing said clamping bars on said cylinder, of a cylindrical printing border made up of straight side bars and curved ends bars, the said curved clamping bars and curved printing 105 bars having interlocking engagement.

3. The combination with a cylinder, circumferentially spaced straight clamping bars, coöperating curved end clamping bars and means for adjustably securing said 5 clamping bars on said cylinder, of a cylindrical printing border made up of straight side bars and curved end bars, the said curved clamping bars and curved printing bars having interlocking engagement, and

the bars of said printing border being de- 10 tachably connected at their abutting ends.

In testimony whereof I affix my signature in presence of two witnesses.

CHARLES N. GALLAND.
